(57) **CLAIM**

We claim the ornamental design for a combined handheld laser and camera unit, as shown and described.

DESCRIPTION

FIG. 1 is a top, front and left side perspective view of a combined handheld laser and camera unit showing our new design;

FIG. 2 is a top front and right perspective view thereof;

FIG. 3 is a left side elevational view thereof;

FIG. 4 is a right side elevational view thereof;

FIG. 5 is a rear elevational view thereof;

FIG. 6 is a top plan view thereof; and,

FIG. 7 is a bottom plan view thereof.

The ornamental design which is claimed is shown in solid lines in the drawings. The broken lines in the drawings are for illustrative purposes only and form no part of the claimed design.
